Continuation of application Ser. No. 476,784, Dec. 21, 1954. This application Mar. 23, 1959, Ser. No. 801,408

18 Claims. (Cl. 166—138)

This invention relates to well devices and particularly to well packers adapted to be lowered into well boreholes and actuated to pack off the well borehole against extremely high pressures below the packer.

Packers of the type heretofore employed for such purposes have been constructed in such manner as to require the application of weight or other downwardly directed force through the running-in string or pipe upon which the packer is suspended in the well borehole for setting and for holding the packer in set position within the well. Under such conditions the action of any pressure under the packer is such as to tend to unseat the packer and destroy the packing-off action and therefore such force below the packer must be more than balanced by downward force applied through the running-in string. In wells where the pressures to be retained therein below the packer are extremely high, this arrangement is unsatisfactory for several obvious reasons, among them being the limitations to the downward force that can be safely applied in compression through the running-in string, particularly when such running-in string comprises tubing or other relatively light and flexible pipe.

To overcome the foregoing disadvantages and limitations of the conventional packer, attempts have been made to run in and set packers in an inverted or so-called upside-down position within the well whereby the force necessary to set and retain the packer in set position within the well borehole can be applied as tension through the running-in string and under which conditions the fluid pressure thereunder acts upon the packer in a direction and manner such as to assist in the setting and retention of the packer in set condition within the well, instead of acting in opposition to such setting of the packer as hereinbefore mentioned.

However, the placing of such conventional packers in inverted or so-called upside-down positions within well boreholes is often hazardous, particularly as to their possible subsequent removal from the well, unless suitable modifications and provisions are made for proper control of the packer during the running into the well, the setting and the release and removal from or resetting thereof in the well.

Accordingly, the packing device of this invention is of such construction that after being lowered into the well bore and released, the setting of the packer is then accomplished by pulling up on or applying tension through the running-in string, instead of applying downward force or weight therethrough to the top of the packer as has been a conventional practice heretofore. Consequently, an important feature of the packing device of the present invention is that the tool is set and maintained in set condition by the application of tension rather than compression through the running-in string.

Additionally, the packer of this invention has inherent novel structural features which under normal well conditions permit ready release of the packer for movement and resetting at any desired other location within the well, or permit entire removal of the tool from the well.

2

Another important and novel feature of this invention is found in the construction which, if the packer should become stuck in the well after being set therein for a period of time so that it cannot be released and removed in the normal manner, permits the major and most difficultly drillable portion of the assembly to be detached from the other portion and removed from the well, leaving therein only those stuck portions which may be more easily drilled away or otherwise dislodged from the set position in the well.

It is, therefore, an object of the present invention to provide an improved well packer device which can be actuated and set in operative position by an upward pull thereon, instead of an application of weight on top of the tool.

Another object of the invention is to provide a novel tension operated, so-called upside-down packer for holding high pressures below it, such as when pressurizing, water flooding, formation fracturing, and the like.

Another object of the invention is to provide an improved packer well tool apparatus which can be retrieved by simply lowering the tubing string to actuate a latching mechanism which will then pick up the tool by which it can easily be removed from the well or borehole.

A further object of the invention is to provide a tool as set forth in the preceding object which, in the event the tool cannot be retrieved in the stated manner, can be released at least in part upon further rotation of the drill string or tubing in a right-hand direction and a further upward pull on the drill string or tubing.

These and other objects, advantages and features of novelty will be evident hereinafter.

In the drawings which illustrate a preferred embodiment and such mode of operation of the invention and in which like reference numerals designate the same or similar parts throughout the several views:

Figure 1 is a longitudinal view partly in section of the packer assembly as it appears just prior to being set in a well borehole or casing.

Figure 2 is a view similar to Figure 1 showing the packer after being set in a well casing.

Figure 3 is a view similar to Figure 2 showing the packer after being manipulated for retrieving certain parts thereof from the well.

Figure 4 is an enlarged longitudinal sectional view of the latch housing unit of the packer assembly.

Figure 5 is a cross sectional view taken along the line 5—5 of Figure 4.

Figure 6 is a cross sectional view taken along the line 50 6—6 of Figure 1.

Referring more particularly to the drawing, the packer apparatus of this invention comprises a mandrel 10 having external threads 11 at its upper end by which a top collar assembly 12 is secured thereto, the assembly including a top collar 13 having internal threads 14 for engagement with threads 11 of the mandrel and internal threads 15 for attachment to and support by a running-in string such as a section of drill pipe, tubing or the like. Assembly 12 also includes a latch housing unit 16 having an annular nut retainer 17 which is secured to top collar 13 in any suitable manner, such as by welding 18. The latch housing unit also includes a cylindrical latch housing member 20 which is secured at its upper end portion to nut retainer 17 by threads 19 and is formed at its lower end with an inwardly directed, annular flange 21

65 for supporting and retaining within the annular space thereby formed between the housing member 20 and the exterior of the mandrel, a latching nut 22. Nut 22 is comprised of a plurality of circular segments, each segment having a central, upwardly facing, radial slot 23 formed in the upper end portion thereof, into which extends a downwardly extending rib 24 formed on the

lower end portion of the latching nut retainer 17. This rib and slot arrangement permits the nut segments to move radially in and out within the latch housing, but restrains these segments from rotational movement with respect to the housing. The segmental portions of nut 22 are urged radially inward by a split, resilient clamping ring 25 which encircles the segments and is positioned in circumferential grooves 26 formed in each of the outer faces of the nut segments. The inner faces of the nut segments are formed with internal, upwardly facing, buttress shaped teeth 27 which together form a continuous left-hand thread which matches and is engageable with corresponding downwardly facing buttress threads formed on the upper end portion 28 of a slip rein collar 30 which is in turn slidable longitudinally on mandrel 10.

The lower end of mandrel 10 is formed with external left-hand threads 31 for engaging the internal threads 32 of a packing element supporting sleeve 33 which is thereby normally secured and supported at the lower end of the mandrel. Sleeve 33 may, if desired, be provided with internal threads 34 at its lower end for attachment thereto of tubing or the like apparatus. A packing ring nut 35 is suitably secured on sleeve 33 as by threaded connection 35a, or otherwise formed as an annular enlargement of the sleeve 33 and formed with an upwardly facing annular shoulder 36. An annular packing element 37 surrounds packing element supporting sleeve 33 and is supported on shoulder 36 of nut 35. The packing element may comprise a unitary sleeve of rubber or synthetic rubber, or it may comprise an assembly of a plurality of rings 37a of such material which in either case is expansible radially into engagement with the casing upon application thereto of longitudinal pressure.

A tubular slip expander 38 is slidable on mandrel 10 above packing element 37 and has an internal bore 40 in its upper portion making a sliding fit upon the mandrel 10 and an enlarged bore 41 therebelow making a sliding fit over the upper end portion of the packing element supporting sleeve 33 with the lower end portion thereof forming a downwardly facing annular shoulder 42 which normally abuts the upper end of packing element 37. The lower portion of slip expander 38 is formed with a longitudinally extending slot 43 therethrough and into which a key pin 44 partially extends, the pin being seated in a radial bore 45 extending through the wall of the packing element supporting sleeve 33. A spring 46 which comprises a rod or wire extends transversely through pin 44 and laterally therefrom into seated position within a curved groove 47 formed in the interior surface of the upper bore portion of packing element supporting sleeve 33. By virtue of this construction the key pin 44 is urged inwardly by the spring 46 against the outer surface of mandrel 10.

Slip expander 38 is formed with an upwardly converging frusto-conical, external surface portion 48 terminating in an annular shoulder 49 at its upper end. A plurality of slips 50 surround the slip expander 38 and are slidably supported on the frusto-conical external surface portion thereof by a plurality of flexible slip reins 51 to which they are individually secured by suitable frangible connections which, for example, may comprise shear rivets 52 or the like attachment. The slips 50 are formed with recesses or grooves 53 into which extend the lower ends of the before-mentioned slip reins 51. A plurality of outwardly extending bow springs 54 are provided for making frictional engagement with the inside of a surrounding well casing and are secured as by means of cap screws 55 to the slip rein collar 30. The lower ends of the bow springs 54 bear inwardly upon the lower end portions of the slip reins 51 in grooves or recesses 53 with freedom for limited longitudinal sliding movement therein. A collar or jar ring 56 surrounds and is suitably secured on mandrel 10 as by means of welding at 57 or otherwise.

In the operation of the invention the packer is run or lowered by the running-in string into the well bore or casing C to the desired position with the parts positioned as shown in Figure 1 during the running-in operation. The packer setting operation is then initiated by right-hand rotation of mandrel 10 while simultaneously exerting a relatively light upward pull of the mandrel to bring the latching nut threads 27 upward into engagement with the slip rein collar threads 28. The mandrel is then rotated a sufficient number of turns relative to the collar 30 to screw the threads 28 of the collar 30 from the position shown in Figure 1 downward through and out of engagement with the threads 27 of the latching nut 22 to a position therebelow approximating that shown in Figure 2. During such rotation of the mandrel and latch housing the rotation of the slip rein collar 30 relative to the casing C is prevented by the frictional engagement of bow springs 54 with the wall of the well bore or casing. After threads 27 and 28 have been disengaged in the manner hereinbefore described, a further upward pull or tension applied to the tubing string and mandrel 10 results in movement of the expander 38 upward over slips 50 which will thereby be moved outwardly into casing engaging position. Thereafter, further upward movement of the mandrel will result in application of longitudinal pressure upon the packing element 37 between the shoulder 36 of nut 35 and the shoulder 42 of slip expander 38, whereby the packing element 37 will be expanded radially into sealing engagement with the inside of casing C, as shown in Figure 2.

After the purposes for which the packer has been set have been accomplished and if it is then desired to retrieve the packer from the well borehole, release thereof may normally be accomplished in the following manner.

35 The tension of the running-in string is released and mandrel 10 and sleeve 33 are lowered a short distance relative to the collar 30, slip expander 38 and slips 50 without rotation, during which movement, key pin 44 in sleeve 33 will move downward into engagement with the lower end of slot 43 of the slip expander 38, and further downward movement of the mandrel will then normally apply sufficient downward pressure to the slip expander 38 to cause it to move downward out from under slips 50, thereby normally releasing the slips from casing engagement, 40 and at the same time the packing ring nut 35 will be moved downward relative to the shoulder 42 together with the downward motion of the packing element supporting sleeve 33 and the longitudinal setting pressure on the packer element 37 will thereby be relieved. Following this, the mandrel 10, together with the sleeve 33, packing element 37 and slip expander 38 may be lowered still further until the latch housing unit 16 and housing unit 20 which meanwhile are supported stationary within the casing by the bow springs 54 are moved downward over threaded portion 28 of the slip rein collar 30, whereupon the segments of the latching nut 22 will ratchet completely over and beyond the threaded portion 28 and into substantially the latched position shown in Figure 1. In this position the mandrel may be rotated in either direction, 50 if desired, without placing any strain upon threads 27, 28 or any of the packer parts coupled thereto. After the before-described latching engagement has been effected, an upward pull on the tubing string and mandrel will normally return the parts of the packer substantially to the condition shown in Figure 1, and the packer may then be retrieved as a unit from the well bore or casing.

60 An important advantage of this ratcheting clutch structure is that the packer can be set and released for retrieving by simple rotation in one direction and longitudinal movements of the running-in string, thus eliminating the use of the usual pin and J-slot connection and the necessity of rotation of the running-in string in both left-hand and right-hand directions.

65 Under some conditions, as is well known, such as, for example, where settling upon the top of the packer have

"frozen" the slips and slip expander in the well bore or casing, the packer may thus become stuck in the well and cannot be retrieved in the normal manner hereinbefore described. When this occurs a partial release so as to free the mandrel and bow springs from the stuck parts of the packer for retrieving from the well may be accomplished as follows: Right-hand rotation is first imparted to the tubing string and mandrel to break the left-hand threaded joint at threads 31, 32 which disconnects the mandrel 10 from the packing element supporting sleeve 33, and thereby frees the mandrel 10 to be raised to the position shown in Figure 3. Upon thus raising the mandrel, jar ring collar 56 engages the lower end of the slip rein collar 30 as shown in Figure 3 and applies upward force to the slip rein collar 30 and the connected slips, and upon further elevational movement of the mandrel the slips 50 may be dislodged and moved upwardly and released from the slip expander 38. In the event the slips cannot be released in this manner, the frangible connections 52 will then fracture and the slip reins 51 and bow springs 54 will be raised with the slip rein collar 30, leaving the slips 50, slip cone 38, packing element supporting sleeve 33 and packing element 37 in set position in the well casing. The metallic parts thus left in place in the well are usually made of cast iron or other suitable relatively soft material and may be readily drilled out.

Upon elevation of the mandrel and after the lower end thereof passes the inner end of key pin 44 as shown in Figure 3, this key pin will be moved or thrown inwardly as shown in Figure 3, due to the action of spring 46, and thereby permit the packing element supporting sleeve 33 and possibly the packing element 37, if it is sufficiently free, to drop to the bottom of the well.

If for some reason these parts do not drop freely as they should after the key pin 44 has moved inwardly as described, they may be jarred loose by bumping downward on the top shoulder 49 of expander 38 with suitable tools and thus move the expander down and away from under the slips.

While the invention has been herein illustrated and described in what is now considered to be a preferred embodiment, it is to be understood that the invention is not limited to the specific details thereof, but covers all changes, modifications, and adaptations within the scope of the appended claims.

This is a continuation of application Serial No. 476,784 filed by us December 21, 1954, now abandoned.

We claim:

1. A well packer comprising: a mandrel connectible to a running-in string for moving and setting said packer within a well casing; a collar slidably mounted on said mandrel; latch means for releasably connecting said collar to said mandrel at a predetermined location, against longitudinal sliding movement thereon, said latch means being actuatable to disconnect said collar from said mandrel upon applying simultaneous upward force on and rotation to the mandrel in one direction relative to said collar to permit upward movement of said mandrel relative to said collar, said latch means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander and coupled to said collar for longitudinal movement thereby relative to said mandrel and said slip expander; a packing element supporting sleeve connected to said mandrel and detachable from said mandrel upon rotation of said mandrel relative to said supporting sleeve in said one direction, to permit upward withdrawal of said mandrel, free of said supporting sleeve and said slip expander; and releasable connection means interconnecting said supporting sleeve and slip expander comprising

longitudinal slots formed in said slip expander and key pins extending from said supporting sleeve and resiliently held in slidably position in said slots, said pins and slots normally preventing rotational movement and permitting only limited longitudinal movement between said supporting sleeve and said slip expander while said mandrel is connected to said supporting sleeve the means for resiliently holding said pins being effective on disconnection of said mandrel from said supporting sleeve to withdraw said pins from said slot to permit rotation and unlimited longitudinal sliding movement between said supporting sleeve and said slip expander.

2. A well packer comprising: a mandrel connectible to a running-in string for moving and setting said packer within a well casing; a collar slidably mounted on said mandrel; latch means for releasably connecting said collar to said mandrel at a predetermined location, against longitudinal sliding movement thereon, said latch means being actuatable to disconnect said collar from said mandrel upon applying simultaneous upward force on and rotation to the mandrel in one direction relative to said collar to permit upward movement of said mandrel relative to said collar, said latch means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing engaging and disengaging positions; coupling means connecting said slips to said collar for longitudinal movement thereby relative to said mandrel and said slip expander, said coupling means including frangible means to release said coupling means upon application of force in excess of a predetermined force therethrough between said collar and said slips tending to move said slips to said casing disengaging position; a packing element supporting sleeve connected to said mandrel and detachable from said mandrel upon rotation of said mandrel relative to said supporting sleeve in said one direction, to permit upward withdrawal of said mandrel free of said supporting sleeve, said slip expander and said packing element supporting sleeve; and connection means between said supporting sleeve and slip expander normally preventing rotational movement and permitting only limited longitudinal movement, between said supporting sleeve and said slip expander while said mandrel is connected to said supporting sleeve and operative by disconnection of said mandrel from said supporting sleeve to permit rotation and unlimited longitudinal sliding movement between said supporting sleeve and said slip expander.

3. A well packer comprising: a mandrel connectible to a running-in string for moving and setting said packer within a well casing; a collar slidably mounted on said mandrel; latch means for releasably connecting said collar to said mandrel at a predetermined location, against longitudinal sliding movement thereon, said latch means being actuatable to disconnect said collar from said mandrel upon applying simultaneous upward force on and rotation to the mandrel in one direction relative to said collar to permit upward movement of said mandrel relative to said collar, said latch means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing engaging and disengaging positions; coupling means connecting said slips to said collar for longitudinal movement thereby relative to said mandrel and said slip expander, said coupling means including frangible means to release said coupling means upon application of force in excess of a

predetermined force therethrough between said collar and said slips tending to move said slips to said casing disengaging position; a packing element supporting sleeve connected to said mandrel and detachable from said mandrel upon rotation of said mandrel relative to said supporting sleeve in said one direction, to permit upward withdrawal of said mandrel free of said supporting sleeve, said slip expander and said packing element supporting sleeve; connection means between said supporting sleeve and slip expander normally preventing rotational movement and permitting only limited longitudinal movement, between said supporting sleeve and said slip expander while said mandrel is connected to said supporting sleeve and operative by disconnection of said mandrel from said supporting sleeve to permit rotation and unlimited longitudinal sliding movement between said supporting sleeve and said slip expander; a laterally extending annular shoulder carried adjacent one end of said supporting sleeve; a laterally extending annular shoulder carried adjacent one end of said slip expander, said shoulders being thereby positioned opposite one another; and an annular expandible packing element encircling said supporting sleeve, intermediate said shoulders.

4. A well packer comprising: a mandrel connectible to a running-in string for moving and setting said packer within a well casing; a collar slidably mounted on said mandrel; latch means for releasably connecting said collar to said mandrel at a predetermined location, against longitudinal sliding movement thereon, said latch means being actuatable to disconnect said collar from said mandrel upon applying simultaneous upward force on and rotation to the mandrel in one direction relative to said collar to permit upward movement of said mandrel relative to said collar, said latch means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander and coupled to said collar for longitudinal movement thereby relative to said mandrel and said slip expander; a packing element supporting sleeve connected to said mandrel and detachable from said mandrel upon rotation of said mandrel relative to said supporting sleeve in said one direction, to permit upward withdrawal of said mandrel free of said supporting sleeve, said slip expander and said packing element; connection means between said supporting sleeve and slip expander normally preventing rotational movement and permitting only limited longitudinal movement between said supporting sleeve and said slip expander while said mandrel is connected to said supporting sleeve and operative by disconnection of said mandrel from said supporting sleeve to permit rotation and unlimited longitudinal sliding movement between said supporting sleeve and said slip expander, said connection means including a longitudinal slot in said slip expander, a bore extending laterally through the wall of said supporting sleeve and normally obstructed at its inner end by said mandrel when said mandrel is connected to said supporting sleeve, and a key pin slideable in said bore and normally extending into said slot; and self-actuating means urging said pin to slide in said bore toward said mandrel whereby when said mandrel is disconnected and removed from said supporting sleeve said key pin is freed to slide inward out of said slot.

5. A well packer comprising: a mandrel connectible to a running-in string for moving and setting said packer within a well casing; a collar slidably mounted on said mandrel; latch means for releasably connecting said collar to said mandrel at a predetermined location, against longitudinal sliding movement thereon, said latch means being actuatable to disconnect said collar from said mandrel upon applying simultaneous upward force on

and rotation to the mandrel in one direction relative to said collar to permit upward movement of said mandrel relative to said collar, said latch means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing engaging and disengaging positions; coupling means connecting said slips to said collar for longitudinal movement thereby relative to said mandrel and said slip expander, said coupling means including frangible means to release said coupling means upon application of force in excess of a predetermined force therethrough between said collar and said slips tending to move said slips to said casing disengaging position; a packing element supporting sleeve connected to said mandrel and detachable from said mandrel upon rotation of said mandrel relative to said supporting sleeve in said one direction, to permit upward withdrawal of said mandrel free of said supporting sleeve, said slip expander and said packing element; connection means between said supporting sleeve and slip expander normally preventing rotational movement and permitting only limited longitudinal movement, between said supporting sleeve and said slip expander while said mandrel is connected to said supporting sleeve, and operative by disconnection of said mandrel from said supporting sleeve to permit rotation and unlimited longitudinal sliding movement between said supporting sleeve and said slip expander, said connection means including a longitudinal slot in said slip expander; a bore extending laterally through the wall of said supporting sleeve and normally obstructed at its inner end by said mandrel when said mandrel is connected to said supporting sleeve; and a key pin slideable in said bore and normally extending into said slot; and self-actuating means urging said pin to slide in said bore toward said mandrel whereby when said mandrel is disconnected and removed from said supporting sleeve said key pin is freed to slide inward out of said slot.

6. A well packer comprising: a mandrel connectible to a running-in string for moving and setting said packer within a well casing; a latch housing on said mandrel; a collar slideable on said mandrel and having external, downwardly facing buttress threads thereon; a ratchet latch element in said housing having upwardly facing buttress threads engageable with said downwardly facing buttress threads for releasably connecting said collar to said mandrel at a predetermined location, against longitudinal sliding movement thereon, said latch element being releasable upon applying simultaneous upward force on and rotation to the mandrel relative to said collar to disengage said threads to permit upward movement of said mandrel relative to the said collar; means connected to said collar for making frictional engagement with a surrounding casing; a slip expander slideable on said mandrel; a plurality of slips on said slip expander movable thereon into casing-engaging and disengaging positions; coupling means connecting said slips to said collar for longitudinal movement thereby relative to said mandrel and said slip expander; a packing element supporting sleeve connected to said mandrel; and connection means connecting said packing element supporting sleeve with said slip expander and normally preventing rotational movement and permitting only limited longitudinal sliding movement between said supporting sleeve and said slip expander, whereby after said packer has been set within a well casing downward longitudinal movement of said mandrel will effect limited downward movement of said supporting sleeve relative to said slip expander after which said connection means will tend to move said slip expander downwardly relative to said slips and thereby permit ratcheting engagement of said buttress threads

of said ratchet latch element with said buttress threads of said collar.

7. A well packer comprising: a mandrel connectible to a running-in string for moving and setting said packer within a well casing; a latch housing on said mandrel having a downwardly directed opening; a collar slideable on said mandrel and having external downwardly facing buttress threads thereon movable therewith through said opening into said housing; a ratchet latch element in said housing having upwardly facing buttress threads engageable with said downwardly facing buttress threads upon movement thereof into said housing for releasably connecting said collar to said mandrel at a predetermined location, against longitudinal sliding movement thereon, said buttress threads of said latch element being releasable from said threads of said collar upon applying simultaneous upward force on and rotation to the mandrel relative to said collar, to permit upward movement of said mandrel relative to the said collar; means connected to said collar for making frictional engagement with a surrounding casing; a slip expander slideable on said mandrel; a plurality of slips on said slip expander movable thereon into casing-engaging and disengaging positions; coupling means connecting said slips to said collar for longitudinal movement thereby relative to said mandrel and said slip expander; a packing element supporting sleeve connected to said mandrel; and connection means between said supporting sleeve and slip expander normally preventing rotational movement and permitting only limited longitudinal movement between said supporting sleeve and said slip expander, whereby after said packer has been set within a well casing downward longitudinal movement of said mandrel will effect limited downward movement of said supporting sleeve relative to said slip expander after which said connection means will tend to move said slip expander downwardly relative to said slips and thereby permit engagement of said buttress threads of said ratchet element with said buttress threads of said collar.

8. A well packer comprising: a mandrel connectible to a running-in string for moving and setting said packer within a well casing; a latch housing on said mandrel having a downwardly directed opening; a collar slideable on said mandrel and having external downwardly facing buttress threads thereon movable therewith through said opening into said housing; a ratchet latch element in said housing having upwardly facing buttress threads engageable with said downwardly facing buttress threads upon movement thereof into said housing for releasably connecting said collar to said mandrel at a predetermined location, against longitudinal sliding movement thereon, said buttress threads of said latch element being releasable from said threads of said collar upon applying simultaneous upward force on and rotation to the mandrel relative to said collar, to permit upward movement of said mandrel relative to the said collar; means connected to said collar for making frictional engagement with a surrounding casing; a slip expander slideable on said mandrel; a plurality of slips on said slip expander movable thereon into casing-engaging and disengaging position; coupling means connecting said slips to said collar for longitudinal movement thereby relative to said mandrel and said slip expander; a packing element supporting sleeve detachably connected to said mandrel; and detachable connection means between said supporting sleeve and slip expander normally preventing rotational movement and permitting only limited longitudinal movement between said supporting sleeve and said slip expander, said detachable connection means comprising a longitudinal slot in said slip expander; a lateral bore in said supporting sleeve, and normally obstructed at its inner end by said mandrel when said mandrel is connected to said supporting sleeve; a key pin slideable in said bore and normally extending into said slot; and means urging said pin to slide in said bore toward said supporting sleeve, whereby after said packer

has been set within a well casing downward longitudinal movement of said mandrel will effect limited downward movement of said mandrel relative to said slip expander after which said connection means will tend to move said slip expander downwardly relative to said slips and thereby permit engagement of said buttress threads of said ratchet element with said buttress threads of said collar.

9. A well packer according to claim 8 in which there is a laterally extending annular shoulder carried on the mandrel thereof adjacent one end of said supporting sleeve; a laterally extending annular shoulder adjacent one end of said slip expander, said shoulders being thereby positioned opposite one another; and an expandable packing element on said supporting sleeve, intermediate said shoulders.

10. A well packer comprising: a mandrel connectible to a running-in string for moving and setting said packer within a well casing; a collar slidably mounted on said mandrel; latching means for releasably connecting said collar to said mandrel at a predetermined location against longitudinal sliding movement thereon, said latching means being actuatable to disconnect said collar from said mandrel upon applying simultaneous upward force on and rotation to the mandrel in one direction relative to said collar to permit upward movement of said mandrel relative to said collar, said latching means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing engaging and disengaging positions; coupling means connecting said slips to said collar for concurrent longitudinal movement therewith relative to said mandrel and said slip expander, said coupling means including frangible means which undergo fracture so as to release said coupling means upon application of upward force in excess of a predetermined

40 force therethrough between said collar and said slips tending to move said slips to said casing disengaging position; a packing element supporting sleeve connected to said mandrel and detachable from said mandrel upon rotation of said mandrel relative to said supporting sleeve in said one direction, to permit upward withdrawal of said mandrel free of said supporting sleeve and said slip expander; connection means interposed between said supporting sleeve and said slip expander normally permitting limited longitudinal movement therebetween but restraining relative rotation therebetween; and means rendering 50 said connection means inoperative upon disconnection of said mandrel from said supporting sleeve so as to permit rotation and unlimited sliding movement between said supporting sleeve and said slip expander.

11. A well packer comprising: a mandrel connectible to a running-in string for moving and setting said packer within a well casing; a collar slidably mounted on said mandrel; latching means for releasably connecting said collar to said mandrel at a predetermined location against longitudinal sliding movement thereon, said latching means being actuatable to disconnect said collar from said mandrel upon applying simultaneous upward force on and rotation to the mandrel in one direction relative to said collar, said latching means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing engaging and disengaging positions; coupling means connecting said slips to said collar for concurrent longitudinal movement therewith relative to said mandrel and said slip expander, said coupling means including frangible means which undergo fracture so as

to release said coupling upon application of upward force in excess of a predetermined force therethrough between said collar and said slips tending to move said slips to said casing disengaging position; a packing element supporting sleeve connected to said mandrel and detachable from said mandrel upon rotation of said mandrel relative to said supporting sleeve in said one direction, to permit upward withdrawal of said mandrel free of said supporting sleeve and said slip expander; connection means interposed between said supporting sleeve and said slip expander normally permitting limited longitudinal movement therebetween but restraining relative rotation therebetween; means rendering said connection means inoperative upon disconnection of said mandrel from said supporting sleeve so as to permit rotation and unlimited sliding movement between said supporting sleeve and said slip expander; a laterally extending annular shoulder formed adjacent one end of said supporting sleeve; a laterally extending annular shoulder formed adjacent one end of said slip expander, said shoulders being positioned opposite one another; and an annular expandable packing element encircling said supporting sleeve intermediate said shoulders.

12. A well packer comprising: a mandrel connectible to a running-in string for moving and setting said packer within a well casing; a collar slidably mounted on said mandrel; latching means for releasably connecting said collar to said mandrel at a predetermined location against longitudinal sliding movement thereon, said latching means being actuatable to disconnect said collar from said mandrel upon applying simultaneous upward force on and rotation to the mandrel in one direction relative to said collar to permit upward movement of said mandrel relative to said collar, said latching means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing-engaging and disengaging positions; coupling means connecting said slips to said collar for concurrent longitudinal movement therewith relative to said mandrel and said slip expander, said coupling means including frangible means which undergo fracture so as to release said coupling means upon application of upward force in excess of a predetermined force therethrough between said collar and said slips tending to move said slips to said casing-disengaging position; a packing element supporting sleeve connected to said mandrel and detachable from said mandrel upon rotation of said mandrel relative to said supporting sleeve in said one direction, to permit upward withdrawal of said mandrel free of said supporting sleeve and said slip expander; an abutment element formed on said mandrel at a point normally spaced below said collar, said abutment element being movable upwardly to engage said collar when said mandrel is detached from said packing element supporting sleeve and undergoes said upward withdrawal so as to thereby transmit an upward force upon said slips through said coupling means; connection means interposed between said supporting sleeve and said slip expander normally permitting limited longitudinal movement therebetween but restraining relative rotation therebetween; and means rendering said connection means inoperative upon disconnection of said mandrel from said supporting sleeve so as to permit rotation and unlimited sliding movement between said supporting sleeve and said slip expander.

13. A well packer comprising: a mandrel connectible to a running-in string for moving and setting said packer within a well casing; a collar slidably mounted on said mandrel; latching means for releasably connecting said collar to said mandrel at a predetermined location against longitudinal sliding movement thereon, said latching means being actuatable to disconnect said collar from said mandrel upon applying simultaneous upward force on

and rotation to the mandrel in one direction relative to said collar to permit upward movement of said mandrel relative to said collar, said latching means also being actuatable to reconnect said collar to said mandrel at said predetermined location upon applying downward longitudinal movement of said mandrel with respect to said collar; means connected to said collar for making frictional engagement with a surrounding casing; a slip expander slideable on said mandrel; a plurality of slips on said slip expander movable thereon into casing-engaging and disengaging positions; coupling means connecting said slips to said collar for concurrent longitudinal movement therewith relative to said mandrel and said slip expander, said coupling means including frangible means which undergo fracture so as to release said coupling upon application of upward force in excess of a predetermined force therethrough between said collar and said slips tending to move said slips to said casing disengaging position; a packing element supporting sleeve connected to said mandrel and detachable from said mandrel upon rotation of said mandrel relative to said supporting sleeve in said one direction, to permit upward withdrawal of said mandrel free of said supporting sleeve and said slip expander; an abutment element formed on said mandrel at a point normally spaced below said collar, said abutment element being movable upwardly to engage said collar when said mandrel is detached from said packing element supporting sleeve and undergoes said upward withdrawal so as to thereby transmit an upward force upon said slips through said coupling means; connection means interposed between said supporting sleeve and said slip expander normally permitting limited longitudinal movement therebetween but restraining relative rotation therebetween; means rendering said connection means inoperative upon disconnection of said mandrel from said supporting sleeve so as to permit rotation and unlimited sliding movement between said supporting sleeve and said slip expander; a laterally extending annular shoulder formed adjacent one end of said supporting sleeve; a laterally extending annular shoulder formed adjacent one end of said slip expander, said shoulders being positioned opposite one another; and an annular expandable packing element encircling said supporting sleeve intermediate said shoulders.

14. A well packer comprising: a mandrel connectible to a running-in string for moving and setting said packer within a well casing; a collar longitudinally slidably mounted on said mandrel; latching means fixed to said mandrel and selectively operable to lock said collar against longitudinal sliding movement relative to said mandrel; means connected to said collar for making frictional engagement with said casing to thereby frictionally restrain longitudinal movement of said collar relative to said casing; a slip expander longitudinally slidably carried by said mandrel and formed with a horizontal shoulder; a plurality of slips on said slip expander movable thereon into casing engaging and disengaging positions; coupling means connecting said slips to said collar for concurrent longitudinal movement therewith relative to said mandrel; a packing element supporting sleeve forming a downward continuation of said mandrel and formed with a radial extension that is opposite said horizontal shoulder; a resilient annular packing element encircling said packing element supporting sleeve between said shoulder and said radial extension; and connection means interposed between said supporting sleeve and slip expander permitting limited longitudinal movement therebetween, with upward movement of said string with said collar unlocked relative to said mandrel first effecting upward movement of said slip expander to move said slips into casing engagement position whereafter said packing element is compressed between said shoulder and radial extension into sealing engagement with said casing, and with subsequent lowering of said string moving said radial extension away from said shoulder permitting said packing element to retract

into its original diameter whereafter said slip expander may move downwardly to permit said slips to move into a casing disengaging position.

15. A well packer as set forth in claim 14 wherein said packing element sleeve is selectively detachably from said mandrel and said connection means is then rendered inoperative whereby said mandrel may be withdrawn upwardly free of said sleeve and said slip expander, with said coupling means including frangible means that undergo fracture upon application of upward force in excess of a predetermined force therethrough between said collar and said slips tending to move said slips into said casing disengaging position.

16. A well packer comprising: a mandrel connectible to a running-in string for moving and setting said packer within a well casing; a collar longitudinally slidably mounted on said mandrel; latching means fixed to said mandrel and selectively operable to lock said collar against longitudinal sliding movement relative to said mandrel; means connected to said collar for making frictional engagement with said casing to thereby frictionally restrain longitudinal movement of said collar relative to said casing; a slip expander longitudinally slidably carried by said mandrel and formed with a radially extending, annular shoulder; a plurality of slips on said slip expander movable thereon into casing engaging and disengaging positions; coupling means connecting said slips to said collar for concurrent longitudinal movement therewith relative to said mandrel; a packing element supporting sleeve forming a downward continuation of said mandrel and formed with a radial extension that is opposite said annular shoulder; a resilient annular packing element encircling said packing element supporting sleeve between said shoulder and said radial extension; and connection means interposed between said supporting sleeve and slip expander permitting limited longitudinal reciprocative movement therebetween, with upward movement of said string with said collar unlocked relative to said mandrel first effecting upward movement of said slip expander to move said slips into casing engagement position whereafter said packing element is compressed between said shoulder and said radial extension into sealing engagement with said casing, and with subsequent lowering of said string and said supporting sleeve relative to said slip expander moving said radial extension away from said shoulder permitting said packing element to retract into its original diameter whereafter said slip expander may move downwardly to permit said slips to move into a casing disengaging position.

17. A well packer as set forth in claim 16 wherein said packing element sleeve is selectively detachable from

said mandrel and said connection means is then rendered inoperative whereby said mandrel may be withdrawn upwardly free of said sleeve and said slip expander, with said coupling means including frangible means that undergo fracture upon application of upward force in excess of a predetermined force therethrough between said collar and said slips tending to move said slips into said casing disengaging position.

18. A well packer comprising: a mandrel connectible to a running-in string for moving and setting said packer within a well casing; a collar slidably mounted on said mandrel; latching means for releasably connecting said collar to said mandrel at a predetermined location against longitudinal sliding movement thereon, said latching means being actuatable to disconnect said collar from said mandrel upon applying simultaneous upward force on and rotation to the mandrel in one direction relative to said collar to permit upward movement of said mandrel relative to said collar, said latching means also being actuatable to reconnect said collar to said mandrel at said predetermined location upon applying downward longitudinal movement of said mandrel with respect to said collar; means connected to said collar for making frictional engagement with a surrounding casing; a slip expander slidable on said mandrel; a plurality of slips on said slip expander movable thereon into casing engaging and disengaging positions; coupling means connecting said slips to said collar for concurrent longitudinal movement therewith relative to said mandrel and said slip expander; a packing element supporting sleeve connected to said mandrel and detachable from said mandrel upon rotation of said mandrel relative to said supporting sleeve in said one direction, to permit upward withdrawal of said mandrel free of said supporting sleeve and said slip expander; connection means interposed between said supporting sleeve and said slip expander normally permitting limited longitudinal reciprocative movement therebetween but restraining relative rotation therebetween; and means rendering said connection means inoperative upon disconnection of said mandrel from said supporting sleeve so as to permit rotation and unlimited sliding movement between said supporting sleeve and said slip expander.
